UNITED STATES PATENT OFFICE.

WILLIAM HUME LOGAN, OF LOUISVILLE, KENTUCKY, ASSIGNOR TO THE
DOW WIRE WORKS COMPANY, OF SAME PLACE.

LUGGAGE-CARRIER FOR BICYCLES.

SPECIFICATION forming part of Letters Patent No. 595,185, dated December 7, 1897.

Application filed January 27, 1896. Serial No. 577,054. (No model.)

To all whom it may concern:

Be it known that I, WILLIAM HUME LOGAN, of Louisville, in the county of Jefferson and State of Kentucky, have invented certain new and useful Improvements in Luggage-Carriers for Bicycles; and I do hereby declare that the following is a full, clear, and exact description of the invention, which will enable others skilled in the art to which it applies to make and use the same, reference being had to the accompanying drawings, and to the letters of reference marked thereon, which form part of this specification.

This invention relates to certain improvements in luggage-carriers or children's seats for bicycles or similar vehicles used for carrying various articles or children.

The object of the invention is to provide a device of this character simple in construction, cheap to manufacture, and composed of a minimum number of parts.

The invention consists in certain novel features of construction and in combinations and arrangements of parts more fully described hereinafter and particularly pointed out in the claim.

Referring to the accompanying drawings, Figure 1 is a side elevation of a carrier, showing the position which it assumes upon being attached to a bicycle. Fig. 2 is a perspective view representing the carrier in position. Fig. 3 is a side elevation showing the position of child upon carrier in use.

Like letters of reference indicate the same parts throughout the different views.

In the accompanying drawings a part of the framework of an ordinary bicycle is shown.

j indicates the carrier, formed in the shape of a fender and having its front end raised to a semi-inverted position. Side bars or supports *j'* are connected to the bottom of the carrier at its front lower end and extend up and are fastened at *j''* near the upper front body portion thereof. The cross-bar *j''* connects the wirework of the said body portion and acts as a brace for the entire upper part of the wirework. *j''* is the main outer brace-wire, fastened at its front end to

the bar *j'* and curved in such a way as to conform to the shape of the frame proper and having its free upper end *a* bent over to embrace the handle-bar *e*. The carrier *j* is then allowed to swing down into its normal position, as shown in Fig. 2, and the spring-arms *b b* are brought around on each side of the handle-bar and spring around the vertical post *f* directly below the handle-bar coupling or sleeve.

Located on the under side of the body of the carrier are rearwardly-extending arms *h*, having their outer free ends curved under and then outward to form a clamp to embrace and extend under the head-cone *l* and above the crown-piece *g* of the bicycle and between the forks *i*. The rods *c d* are attached to carrier *j* at a point a sufficient distance from said rods as to allow the clamping-arms to spring vertically, thereby increasing or decreasing the distance between said rods *c d* and the hooks *a* and enabling the complete carrier to be adjusted to any of the different forms of cycles.

There are a series of side braces extending from the lower outer edges of the depressed portion of the seat and connected at their upper portions to the side bars or braces.

The device is very simple and cheap in construction, easily attached to any of the well-known forms of cycles now in use, and one that is easily adjusted to any desired height or position, and preferably made of wire.

It is evident that various slight changes might be made in the forms, constructions, and arrangements of the parts described without departing from the spirit and scope of my invention. Hence I do not wish to limit myself to the exact construction herein set forth, but consider myself entitled to all such changes as fall within the spirit and scope of my invention.

Having thus fully described my invention, what I claim as new, and desire to secure by Letters Patent of the United States, is—

A carrier for bicycles consisting of a body-seat and foot-rest composed of wire-netting having outer wires conforming to the curvature of the carrier and hooked to the handle-

bar, side wires extending from the foot-rest to the top of the outer wires and attached thereto, central spring-arms clamping the vertical post, and arms extending over the top and underneath the fork-crown clamping the same, said arms being attached to the body of the carrier, as set forth.

In testimony that I claim the foregoing as my own I affix my signature in presence of two witnesses.

WILLIAM HUME LOGAN.
